UNIVERSAL TRIPOD

David B. Smith, 42 Ridgedale Ave.,
Madison, N.J. 07940

Filed Feb. 1, 1971, Ser. No. 23,861

Term of patent 14 years

Int. Cl. D16—05

U.S. Cl. D61—1

FIG. 1

FIG. 2

FIG. 3

FIG. 4

FIG. 5

FIG. 6

FIG. 1 is a top plan view of a universal tripod showing my new design;

FIG. 2 is a right side elevational view of FIG. 1, the left side being a mirror image thereof;

FIG. 3 is a front elevational view of FIG. 1;

FIG. 4 is a rear elevational view of FIG. 1;

FIG. 5 is a bottom plan view of FIG. 1;

FIG. 6 is a rear and top perspective view of FIG. 1.

I claim:

The ornamental design for a universal tripod, substantially as shown and described.
